UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

TIME-LIMIT DASH-POT.

No. 821,431.

Specification of Letters Patent.

Patented May 22, 1906.

Application filed July 25, 1903. Serial No. 166,999.

To all whom it may concern:

Be it known that I, WILLIAM B. POTTER, a citizen of the United States, residing at Schenectady, in the county of Schenectady and State of New York, have invented certain new and useful Improvements in Time-Limit Dash-Pots, of which the following is a specification.

This invention relates to time-limit devices for electric switches, and especially for central station installations in distribution systems. It is desirable to retard the action of circuit-breakers or automatic switches at a main or sub station so that the service will not be interrupted by a temporary overload, which might be so brief as not to endanger the apparatus. For instance, where several generators are used, it is customary to connect said generators in parallel to bus-bars common to all, from which feeder-circuits are led out to various parts of the system. Between each generator and the bus-bars is interposed an automatic circuit-breaker responsive to an overload on that particular generator. So, also, each feeder-circuit is provided with an automatic circuit-breaker responsive to an overload on that particular circuit. In case of an overload on one of the feeder-circuits it is desirable to check the opening of the generator-breakers for a second or two until after the feeder-breaker has opened, because if the excessive load be removed by the opening of the feeder-breaker this leaves the tardily-operating generator-breakers closed and the machines still connected with the bus-bars and supplying the other feeders. If no retarding device is used, all the generator-breakers are liable to open at the same time that any one of the feeder-breakers opens, and so cut off the station and shut down the whole system.

My invention has especial reference to an improved time-limit or retarding device for the generator-breakers, though it is applicable to relay-switches or other forms of circuit-controllers. It consists of a dash-pot having a movable abutment, preferably a vibrating blade containing a hole controlled by a check-valve opening freely in one direction of movement of the blade. Projecting from the blade is an arm normally supporting a plunger, which is pivotally attached to the armature of the overload-magnet of an automatic circuit-breaker of standard form. When

the magnet is energized, the plunger is depressed, forcing the blade to swing through the liquid in the dash-pot until the plunger slips off the arm. This provides for a small movement while actuating the dash-pot and freedom for quick unobstructed action independent of the dash-pot after expiration of the time for which it is set. An action of this kind is essential in operating an automatic circuit-breaker, as the momentum of the tripping-armature is necessary to overcome the friction of the locking mechanism. It is also desirable in circuit-closers to prevent burning the contacts by a slow approach. For adjusting the time limit there is a by-pass around the blade, the opening in which can be regulated by an adjusting-screw.

To illustrate the construction and operation of my time-limit device, I have shown it applied to an automatic circuit-breaker of well-known construction, the accompanying drawing being a front elevation of the same, partly in section:

The overload-coil 1 has the usual armature 2, controlling the tripping-latch 3. A plunger 4 is connected with the armature, preferably by means of the pivoted links 5 6, which constitute a toggle for a purpose hereinafter set forth. Lugs 7 on the links lock the toggle just after its middle joint passes the dead-center, to which it is urged by a spring 8, attached, preferably, to an arm 9 on the link 6 and to the armature and operating to hold the toggle normally extended.

The plunger works through a hole in the lid of the receptacle 10, being held up by a light spring 11, abutting between said lid and a collar 12 on the plunger. The spring may be inclosed in a box 13, integral with the lid of the dash-pot and having a screw-cover 14 to limit the upward play of the plunger.

In the dash-pot is a movable abutment, preferably a blade 15, pivoted, preferably, on the lower edge of a rib 10', extending entirely across the lid 10' of the receptacle. On the blade is an arm 16, extending upward at an angle under the lower end of the plunger. The arm is so constructed that the portion which sustains the plunger will be withdrawn when the blade has moved a predetermined angular distance, and thus permit the plunger to drop freely. This is readily accomplished by letting the plunger rest on the edge of the arm, so that the angular movement of the

arm from its normal position will carry said edge out of line with the plunger and permit the latter to slip off. In the drawing the arm is shown provided with a hole 17 large enough to let the plunger pass through it, and the plunger rests normally on the outer edge of the hole. The bottom of the receptacle is concentric with the pivot of the blade, whose edge fits close to said bottom. The dash-pot is filled with liquid, such as oil or glycerin, and the flow of this liquid from one side of the dash-pot to the other when the blade swings from right to left (in the drawing) is regulated by a screw 18, controlling a by-pass 19, preferably in the rib 10'. The return movement of the blade to its normal position is facilitated by a hole 20 in the blade controlled by a check-valve, such as the flap-valve 21 on the front of the blade, which closes the hole when the blade swings from right to left, but opens freely when the blade returns.

The operation is as follows: The energizing of the overload-magnet pulls down the armature, which pushes down the plunger, and thereby depresses the arm and swings the blade to the left. The resistance of the liquid causes the blade to move slowly, and thus retards the action of the tripping devices until the angular movement of the arm brings the hole fully under the plunger, which instantly slips through said hole and permits a sudden operation of the tripping mechanism.

35 In case it is desired to trip the breaker by hand the rod 22, attached to the arm 9, is pulled down, which breaks the toggle and permits the armature to be depressed without actuating the plunger.

40 In accordance with the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

50 1. The combination with an automatic circuit-breaker, of a dash-pot having a pivoted abutment therein, means for connecting said abutment with the tripping mechanism of the breaker, and means for automatically disconnecting it after a definite time of movement.

60 2. The combination with an automatic circuit-breaker, of a dash-pot having a pivoted abutment therein, an arm on said abutment, a plunger connected with the tripping mechanism of the breaker and bearing on said arm, and means permitting said plunger

to have a free movement independent of said arm after a predetermined time of movement together.

65 3. The combination with an automatic circuit-controller, of a dash-pot having a pivoted abutment therein, an arm on said abutment, and a plunger connected with the tripping mechanism of said breaker and bearing on said arm adjacent to the edge thereof.

4. The combination with an automatically tripped circuit-controller, of a dash-pot comprising a receptacle having a curved bottom, a blade operatively connected to the tripping mechanism of said controller and pivoted in said receptacle concentrically with said bottom, an arm on said blade, a by-pass, and a regulating-screw therefor.

5. The combination with an automatically-tripped circuit-controller, of a dash-pot comprising a receptacle having a curved bottom, a blade operatively connected to the tripping mechanism of said controller and pivoted in said receptacle concentrically with said bottom and having a hole, a check-valve controlling said hole, an arm on the blade, and a plunger resting on the edge of said arm.

6. The combination with an automatic circuit-breaker, of a dash-pot, a plunger, and a toggle connecting said plunger with the tripping mechanism of the breaker.

7. The combination with an automatic circuit-breaker, of a dash-pot, a plunger, two links composing a toggle connecting said plunger with the tripping mechanism of the breaker, an arm on one of said links, and a spring and a rod attached to said arm.

8. The combination with an automatic circuit-breaker, of a dash-pot, a plunger, two links composing a toggle connecting said plunger with the tripping mechanism of the breaker, an arm on one of said links, a spring and a rod attached to said arm, and means for holding said toggle normally extended.

105 9. The combination with an automatic circuit-controller, of a receptacle having a curved bottom, a lid having a rib extending across the entire width thereof, and containing a by-pass, a blade pivoted on the lower edge of said rib and fitting the curved concentric bottom of the receptacle, an arm on the blade, a box on top of the lid having a cover, a plunger passing through the box and bearing on the arm, a collar on the plunger inside the box, and a spring abutting between said collar and the bottom of the box.

In witness whereof I have hereunto set my hand this 23d day of July, 1903.

WILLIAM B. POTTER.
